UNITED STATES PATENT OFFICE.

EDWARD H. BELDEN, OF DETROIT, MICHIGAN, ASSIGNOR TO PACKARD MOTOR CAR COMPANY, OF DETROIT, MICHIGAN, A CORPORATION OF MICHIGAN.

DOOR-LATCHING MEANS.

1,339,492.

Specification of Letters Patent. Patented May 11, 1920.

Application filed October 4, 1916. Serial No. 123,721.

To all whom it may concern:

Be it known that I, EDWARD H. BELDEN, a citizen of the United States, and resident of Detroit, Wayne county, State of Michigan, have invented certain new and useful Improvements in Door-Latching Means, of which the following is a specification.

This invention relates to motor vehicles, and particularly to the door latching means therefor.

One object of the invention is to provide a door latch for use on automobile doors whereby the door will be securely latched regardless of the twisting or other exceptional movement of the car body.

Another object of the invention is to provide a latch which will remain in latched position and permit separable movement of the door in relation to the door jamb.

Another object of the invention is to prevent the parts of the latch from inadvertently separating.

Another object of the invention is to arrange the several parts so that a maximum of strength and safety in operation will be secured.

Another object of the invention is to provide operating parts of simple construction and substantial proportions whereby dependable action is assured under all conditions.

Another object of the invention is to provide a means for holding the latch securely in latched position until manually released.

Further objects will be evident from the following description taken in connection with the drawings which form a part hereof and in which:

Figure 1 is a plan sectional view of a portion of the door and door jamb as used in automobile construction and embodying the invention;

Fig. 2 is a view of the invention from the outside of the door with the outer plates of the door and door jamb partially broken away.

Fig. 3 is a view of the invention as shown in Fig. 2 with the door sprung to a slightly separated position from the door jamb; and

Fig. 4 is a plan sectional view of another form of the invention; and

Fig. 5 is a plan sectional view showing another form of the invention.

The invention is shown in the accompanying drawings as adapted to automobile body 55 and door construction though it must be understood the following description will apply to the invention as it may be used on or in connection with, any door or other device desired to be latched or locked.

In the drawings a section 10 of the automobile body is shown formed with a jamb portion 11 stepped as customary in door construction of this type and receiving a correspondingly stepped edge face of a door section 12. The jamb is fitted with a strike member 13 shown as a bolt, rectangular in cross section and sliding in openings 14 through end walls 15 and 16 of a suitable casing 17 arranged in the face of the jamb 11. The strike member 13 is beveled at the contacting end 18 thereof and has a transverse-squared groove 19 in the outer face thereof immediately next said beveled end and outside the wall 16 of the casing 17. The strike member 13 has a limited yielding movement whereby it is made recedable in the casing 17 and is normally held in mid position by a pair of oppositely coiled springs 20 and 21 mounted on stud pins 22 projecting outwardly from the inner wall of the casing 17, said springs having the inner ends thereof extending into slots in the stud pins and their outer ends extending downwardly immediately behind the strike member and contacting with stop pins 23 and 24 extending from the inner wall of the casing.

The ends of said springs 20 and 21 where they extend below the stop pins 23 and 24 contact with two pins 25 and 26 extending inwardly from the strike member 13, the spring 20 normally retaining the beveled contact end of the strike member from receding into the jamb and the spring 21 normally retaining said strike member from being moved in the opposite direction, such movement being further limited in a positive manner by a pin 27 entering through said strike member adjacent the end wall 16. The strike member 13 is thus spring held to a normal mid position and the beveled end may recede into the face of the

jamb or may be withdrawn to a limited extent, always being returned however, by the springs 20 and 21 to normal mid position with the squared groove 19 immediately 5 outside the face of the jamb.

The door 12 is formed as hereinbefore mentioned with the edge face stepped to properly meet the door jamb and is further recessed at 28 where it meets the strike 10 member 13 on closing. A latch casing 29 is fitted in the door and comprises a rear wall 30 and top and bottom walls 31 between which a latch member 32 is pivotally mounted on a pin 33, said latch member being substantially hook shaped having a hooked end 34 projecting from the inner face of the door into the recess 28 and normally held in such position by toggle levers 35 and 36 jointed together at 37 and pivotally 15 fastened at one end thereof to a pin 38 extending through a groove 39 in the latch member 32 and at the opposite end thereof to a pin 40 extending between the walls 31 of the latch member casing. A 20 spring 41 is secured around the pin 40 whereby the toggle is normally held with the joint thereof bearing toward the rear wall 30 of the casing 29 and thus locks the latch member 32 with the hooked end 34 25 thereof in its projected position so that when the door is being closed against the jamb said latch member meets the beveled end of the strike member 13 and forces it to recede against the pressure of the spring 30 until the latch member has passed and the strike member is free to spring back to normal position immediately in front of the hooked end of the latch member and thus engage and retain the door in its closed 35 position.

To further secure the door in closed position and prevent the hooked member 32 from unlatching, a finger 42 is provided, said finger being pivotally secured at one 40 end thereof on a pin 43 extending between the walls 31 of the latch member casing, and said finger extending along immediately next the pivoted end of the latch member 32 to the squared groove 19 in the strike 45 member 13 where said finger is turned inwardly at 44 and engages with said groove and is held normally in such position by a spring 45 encircling the pin 43.

The door is thus securely retained in its 50 closed position as any movement inwardly or vertically is prevented by the rigid construction of the several parts, the outward swing of the door is prevented by the engagement of the hooked end of the latch 55 member 32 behind the beveled end of the strike member 13, and finally any tendency of the door to unlatch by separating directly away from the jamb is prevented by the in-turned end of the finger 42 which engages 60 with the squared groove 19 of the strike 65

member 13 and will withdraw said strike member from the door jamb to always have the strike member and latch member in latched relation one to the other, such movement of the door directly away from the jamb being further positively prevented when the pin 27 extending through the strike member 13 meets the end wall 16 of the strike member casing.

To unlatch the door a button 46 is provided on the inside of the door and contained within a shell 47 secured to the inner face of the door and spring held to its projecting position by a spiral spring 48 encircling the shank 49 of said button, said shank extending through a suitable orifice in the rear wall of the latch member casing 30 and contacting with the toggle lever 35 immediately next the joint thereof. Pressure on the button will thus operate the 85 toggle joint moving the same to the position shown in dotted lines Fig. 1, and withdrawing the hooked end of the latch member 32 from engagement with the strike member 13.

Co-incidently with the withdrawing of the 90 hooked end of the latch member from the strike member as above explained the inwardly turned end 44 of the finger 42 is moved from engagement with the squared groove 19 in the strike member 13. This is 95 accomplished by the cam shaped pivoted end 50 of the latch member which contacts with the finger 42 adjacent the pivotal point thereof and moves the inturned end outwardly. Thus if the button is only partially depressed, it will be sufficient to unlatch the door as the finger is free of the strike member and the latch member is turned so that the hooked end is angularly set to the strike member and further outward pressure on the door will cause the strike member to recede as on the closing 100 of the door.

In closing the door as hereinbefore explained the strike member, after receding 110 to permit the latch member to pass, will return to its normal position, the finger 42 giving against the pressure of the spring 45 to permit the end of the strike member to extend until the inwardly turned end of 115 said finger can interlock in the squared groove 19 of said strike member. It will also be noticed that the contacting faces of the interlocking parts are never rigidly held in relation to one another and no damage can be done by violently closing the door even when strained from the normal hung position. In the form shown in Fig. 4 the strike member 13^a is arranged similarly to the strike member 13 hereinbefore described 120 and has the groove 19^a extending transversely of the inner face and immediately adjacent the beveled end.

The latch member 32^a is pivoted on the pin 33^a substantially in alignment with the 130

inner face of the strike member and has the hooked end 34^a slotted at 51 to receive a finger 42^a pivoted on the same pin 33^a with the latch member 32^a and having a toothed end 44^a extending into the groove 19^a in the strike member. The finger 42^a is springheld in position to engage with the groove 19^a by the spring 52 recessed into the latch member; the outward movement of 10 said finger being limited by a stop pin 53 carried by said latch member.

From the above description it will be readily understood that the action in closing the door with the form of the invention 15 shown in Fig. 4 is the same as that described with reference to Figs. 1, 2 and 3, that is the strike member recedes as the door is closed and returns on the outside of the latch member until the end of the spring 20 finger 42^a interlocks with the strike member in the groove 19^a. In opening the door the location of the pivot pin 33^a permits the latch member to swing to the position shown in dotted lines and clear of the strike member. If the button 46^a is only pressed sufficiently to move the toggle joint 37^a to partially withdraw the hooked end of the latch member and further outward pressure is made upon the door the latch member with 30 the finger carried thereby will be forced to recede until clear of the strike member.

In the form of the invention shown in Fig. 5 the strike member 13^b is similar to that shown in Figs. 1, 2 and 3 having the 35 squared groove 19^b and the spring 21^b yieldingly retaining said strike member in the casing 17^b, the action of said spring as also the receding travel of the strike member being limited by a stop pin 54.

40 The latch member 32^b in this form is similar to an ordinary latch bolt and is springheld to its projected position by a spring 20^b arranged in the latch member casing and similar to the spring 20 hereinbefore described. The outward movement 45 of the latch member is limited by a stop pin 55 and in closing the door said latch member will recede and pass by the strike member till free to project behind it as in 50 an ordinary latch.

The latch frame however, is formed with a projection 56 corresponding to the inwardly turned end 44 of the finger 42 as hereinbefore described, said projection 56 55 entering the groove 19^b when the door is closed. Thus when there is any movement of the door to part directly from the jamb the projection 56 will draw the strike member 13^b with it and maintain the same relative latched position between said strike and latch members.

To open the door with the form shown in Fig. 5 a button 46^b is provided on the inner side of the door and extends through to 60 contact with one arm of a bell crank 57

pivoted in the latch member casing. The other arm of said bell crank is slotted at 58 and has a pin 59 from the latch member 32^b extending therethrough and on pressing the button the bell crank is thus operated to 70 withdraw the latch member past the end of the strike member and permit the door to be swung open. Although certain specific embodiments of the invention have been described in the above specification, it 75 should be understood that further changes in the construction and arrangement of the coöperating parts may be made without departing from the spirit and scope of the invention as expressed in the following 80 claims.

Having thus described my invention, what I claim and desire to secure by Letters Patent is:—

1. A door latch comprising a yieldably 85 mounted projecting strike member, a latch member and means separate from and operative with said latch member for preventing independent separating movement of said strike member.

2. A door latch comprising a spring held 90 projecting strike member, a latch member and means separate from and operative with said latch member for interlocking said strike member against independent separating movement.

3. A door latch comprising a strike member spring held to a mid position and having a beveled end transversely grooved, a latch member contacting with said strike member, 100 a spring held finger engaging with the groove in said strike member and means for withdrawing said latch member and said finger from engagement with said strike member.

4. A door latch comprising a strike casing, a springheld strike in said strike casing, a latch casing, a latch pivoted in said latch casing and substantially hook shaped and engaging said strike, a finger pivoted in said 110 latch casing and engaging said strike and operatively controlled by said latch, and means for withdrawing said latch from engagement with said strike.

5. The combination with a door element 115 and a jamb element, of a strike casing, a strike member reciprocally mounted in said strike casing and having a transversely grooved beveled outer end, a pin limiting the reciprocal movement of said strike member, a pair of oppositely coiled springs contained in said strike casing and yieldingly retaining said strike member in a mid position, a latch member secured to the other of said elements and engaging said strike member and a spring held finger operatively connected to said latch member and interlocking with the transverse groove in said strike member.

6. The combination with a door element 130

and a jamb element, of a strike member having a beveled end and transversely grooved adjacent thereto and yieldingly supported in one of said elements, a latch member casing arranged in the other of said elements, a latch member substantially hook shaped to engage with the beveled end of said strike member and having one end thereof cam shaped and pivoted in said casing, a finger pivoted in said casing and spring held against the cam shaped end of said latch member and inwardly turned to interlock with the transverse groove in said strike member and means operatively engaging said latch member for withdrawing said latch member and said finger from engagement with said strike member.

7. The combination with a door element and a jamb element, of a strike member yieldably supported in one of said elements and having a beveled end transversely grooved, a latch member casing, a latch member pivoted in said latch casing and engaging with said strike member, means for holding said latch member in engagement with said strike member, means for withdrawing said holding means and a finger pivotally arranged on said latch member and spring held into engagement with the transverse groove in said strike member.

8. The combination with a door element and a jamb element, of a strike member yieldably supported in one of said elements, and having a beveled end transversely grooved, a latch member pivotally supported in the other of said elements and engaging with said strike member to prevent relative lateral movement and a spring held finger pivotally supported on said latch member and interlocking with the transverse groove in said strike member to prevent relative endwise movement.

9. The combination with a door element and a jamb element, of a strike member movably mounted on one of said elements and spring held to an inner position and having a transverse groove adjacent the outer end thereof, means carried by the other of said elements and engaging with the groove in said strike member to prevent relative separable movement in one direction and a latch member recedably mounted in the other of said elements and spring held to its outer position and engaging with said strike member to prevent relatively separable movement in another direction.

10. The combination with a door element and a jamb element, of a strike member movably mounted on one of said elements and spring held to an inner position and having a transverse groove adjacent the outer end thereof, means carried by the other of said elements and engaging with the groove in said strike member to prevent

relative separable movement in one direction, a latch member recedably mounted in the other of said elements and spring held to its outer position and engaging with said strike member to prevent relatively separable movement in another direction, and a bell crank lever pivoted adjacent said latch member and operatively connected therewith to move the same to its recedable position from engagement with said strike member. 70

11. In a door latch, the combination with the door element and the jamb element, of an extensible projecting strike member carried by one of said elements, a latch member 80 carried by the other of said elements, and arranged to take a position behind the strike member when the door is closed, and means carried by said latch member carrying element and engaging said strike member to prevent relative movement between said strike and latch members.

12. In a door latch, the combination, with the door element and the jamb element, of an extensible projecting strike member carried by one of said elements, and having a transverse notch in one face, a latch member carried by the other of said elements, and arranged to take a position behind the strike member when the door is closed, and 95 means carried by said latch member carrying element, and engaging the notch in said strike member to prevent movement of said member relative to said latch member.

13. In a door latch, the combination with 100 the door element and the jamb element, of a slidable strike member mounted in one of said elements, a pivoted latch member mounted in the other of said elements, means mounted on one member and positively engaging the other member to prevent relative movement between said members and spring operated means acting on said first named means for holding said means in engaging position. 110

14. In a door latch, the combination with the door element and the jamb element, of a slidable strike member, mounted in one of said elements, a pivoted latch member mounted in the other of said elements, means 115 mounted on one member and positively engaging the other member to prevent relative movement between said members, spring operated means acting on said first named means for holding said means in engaging position, and a device acting on said spring operated means to disengage said first named means from said members. 120

15. In a door latch, the combination with the door element and the jamb element, of a 125 slidable strike member mounted in one of said elements, equalized spring means tending to hold said strike member in mid position with one end projecting from said element, a latch member, adapted to engage 130

said strike member, carried by the other of said elements, and a finger also mounted in said latch member carrying element and adapted to engage said strike member and 5 prevent movement of said strike member relative to said latch member.

16. In a door latch, the combination of a door element and a jamb element, of a slide-
able strike member mounted in one of said

elements, a latch member mounted in the 10 other of said elements, said strike member having a notch therein, and a finger mounted on said latch carrying element for engag-
ing said notch and holding said strike mem-
ber in latching engagement with said latch 15 member.

In testimony whereof I affix my signature.
EDWARD H. BELDEN.
